UNITED STATES PATENT OFFICE.

JAMES C. THOMPSON, OF LEMOYNE, PENNSYLVANIA.

TROLLEY-SWITCH.

1,208,048.

Specification of Letters Patent. Patented Dec. 12, 1916.

Application filed February 25, 1915, Serial No. 10,556. Renewed May 23, 1916. Serial No. 99,438.

To all whom it may concern:

Be it known that I, JAMES C. THOMPSON, a citizen of the United States, residing at Lemoyne, in the county of Cumberland and

5 State of Pennsylvania, have invented certain new and useful Improvements in Trolley-Switches, of which the following is a specification.

This invention relates to switches to be 10 associated with the working conductor of an electric railway, in a manner to cause the opening or closing of a circuit by the passage of a trolley or other form of current collector, which for convenience I shall hereinafter refer to as the trolley.

The invention has for its object to provide a device of this kind which will be actuated by a bodily movement of the trolley wire developed by the pressure of the trolley, and 20 which will, therefore, develop its movements gradually during the approach and departure of the trolley and be very much more reliable in service and durable in use, than the so-called trigger or other devices located 25 adjacent to the trolley wire and suddenly receiving the impact of the rapidly moving trolley; to which end one feature of the invention consists in supporting the trolley wire directly upon a movable member of the 30 switch-actuating device, so that the switch-actuating movement is developed from the displacement of the trolley wire (usually upward) in the passage of the trolley.

Another object is to render the device economical in cost by having it take the place 35 of the ordinary trolley wire suspending device in addition to serving its purpose as a circuit closer, to which end the invention is preferably embodied in a supporting shell 40 or housing adapted to receive any suitable type of suspending connections with their usual insulation joints, and having axially mounted therein, a plunger that carries the wire clamp, which plunger has a limited 45 axial movement sufficient to operate the switch, and has mountings which adapt it to support the weight of the trolley wire, as well as limit its upward movement under the trolley pressure.

50 Further objects relate to the details of construction of the preferred embodiment which has been selected for illustration of the general principles of the invention, and can, therefore, be more readily explained in 55 the detailed description which follows.

In the accompanying drawings—Figure 1

is a vertical axial section, and Fig. 2 a top plan view of a switch constructed in accordance with the invention; Fig. 3 suggests the method of putting the switch into use.

60 1 represents a shell or housing which may be of any suitable construction, but which is preferably a cylinder carrying attaching ears 2 for suspending wires or other connections employed in standard trolley practice. Secured to the lower end of the shell 1 is a base 3, preferably united to the shell by a threaded flange 4. Upon this base is mounted a post 5, projecting upwardly within the shell and affording a mounting at its 65 upper end, for the insulating block 6 of a double blade terminal 7; said post providing by its intermediate portion, a guiding slot 8 in which the movable contact 9 of the switch is fulcrumed at 10. Centrally disposed in 70 the base 3 is the axially sliding vertical rod plunger 11, provided with shoulders 12 and 13 which limit its movements, these shoulders being conveniently provided by fitting nuts upon the plunger and securing them by 75 pins 12^a, 13^a, or by threading if it is desirable to make them adjustable. At its upper end, the plunger 11 is connected at 14 with the short arm 9^a of the movable contact lever 9 in relation to impart a direct endwise 80 thrust thereto, and the parts are so designed that the comparatively small range of movement permitted by the shoulders 12 and 13 will develop a movement between the upper 85 end of the lever 9 and the terminal 7, which 90 is ample to break any arcing that develops in the opening of the switch. The plunger 11 is threaded at its lower end 15 to receive directly beneath it and in line with it the shank of the ordinary trolley wire clamp or 95 any other suitable attachment that may be employed for rigidly fixing the trolley wire relatively to the plunger. Terminal 7 may be connected in any suitable manner with a 100 wire for conducting off the current when the switch is closed, as for instance by a binding post 16 introduced through the gasket 17 and through the insulating block 6.

105 The device above described is used as suggested in Fig. 3, by suspending it between the guy wires 18 and attaching to it the trolley wire 19. The weight of the wire 19 normally holds the switch in the position shown in Fig. 1. But as the trolley approaches and presses upwardly upon the 110 wire under the action of its springs, which usually develop a pressure of from twelve

(12) to fifteen (15) pounds at the upper end of the trolley, the plunger 11 will be raised and the switch members 7 and 9 brought together, so that current from the trolley 5 wire passes up through the plunger, the movable switch arm and the terminal 7, to the binding post 16, whence it may be led away to perform any useful purpose which is desired, bearing a definite relation 10 to the arrival or departure of the car. Inasmuch as the upward pressure begins a considerable distance before the trolley reaches the combined switch and hinge and ends only after it has passed a considerable distance beyond, there is considerable range of travel during which the switch is operative. Moreover, it receives its 15 movements quite gradually, rather than from a sudden impact, and the structure is, therefore, very much more durable.

While I have, in making known the principles of operation and construction of the device, referred to a specific application of the device and named certain specific instrumentalities in its operation, it is to be understood that the invention is not necessarily limited to the precise construction for use.

I claim:

30. 1. In a trolley wire switch, the combination of a suitable mounting, a switch carried by said mounting, and a combined trolley-wire-supporting and switch-actuating means, movably carried in and supporting the trolley wire from said mounting, and having suitable connection with the movable member of the switch; said means comprising a vertically sliding rod-plunger having its upper end connected directly to

the switch in position to impart directly 40 thereto, the endwise thrust of the plunger, and having at its lower end and in line with the plunger, a trolley wire clamp through which the plunger receives a direct upward thrust from the lifting of the trolley wire. 45

2. In a trolley wire switch, the combination of a mounting base adapted to be suspended in proper position to support a trolley wire, an axially movable rigid thrust-plunger carried by said mounting and having 50 stop shoulders for limiting its movement therein, a post projecting from said mounting to one side of the plunger, and fixed and movable circuit-closing members mounted on said post; the movable circuit-closing member being connected with the plunger.

3. In a trolley wire circuit closer, the combination of a shell adapted to be suspended in position to support a trolley wire, 60 a base carried by said shell, a post mounted upon the base within the shell, and having a fixed contact suitably mounted thereon; a movable contact arm pivoted to said post, and an axially reciprocating plunger carried by said mounting, with means for limiting its movement therein, connected at one end to the movable switch arm for positively moving the latter in opposite directions, and at its other end adapted to receive a trolley wire attaching means. 65

The foregoing specification signed at Lemoyne, Pennsylvania, this 12th day of February, 1915.

JAMES C. THOMPSON.
